UNITED STATES PATENT OFFICE.

ALBERT B. CLISSON, OF SYRACUSE, NEW YORK, ASSIGNOR, BY MESNE ASSIGNMENTS,
TO THE PROSPERITY COMPANY, INC., OF SYRACUSE, NEW YORK, A CORPOR-
ATION OF NEW YORK.

PRESS.

Application filed March 25, 1924. Serial No. 701,652.

This invention relates to pressing and ironing machines and particularly to improvements in power operated pressing machines.

An object of the invention is to produce a pressing machine having a high compression factor and capable of subjecting work to heavy pressure; and likewise it is an object to produce a machine safe to operate and which is under the control of the operator at all times.

The pressing machine embodies a new and improved combination and preferably employs a prime mover or power means located in the upper portion of the pressing machine which delivers its pressing stroke downwardly upon a power thrust toggle which operates a lever to impose pressure between the contacting pressing members or jaws which are first closed manually by the operator. My improvements in pressing machines embody the additional feature of having wide opening pressing jaws, and, to this end, the press head is caused to move upwardly a long distance thereby affording a wide open clear space which permits the operator to conveniently work while spreading the garment or other work on the buck to be pressed.

The accompanying drawings show a preferred form of the invention illustrating the new combination and arrangement of parts making up my invention, and it is understood that certain changes in arrangement and mode of operation may be carried out without departing from the scope of the invention.

Figure 1 shows a front elevation of the machine in closed position.

Figure 2 illustrates a side view of the pressing machine shown in closed position under final high pressure, and the press is shown in open position by dot and dash lines.

Figure 3 shows a detailed fragmentary view of the motor means and cooperating thrust or power toggle shown in position ready to produce final pressure.

Referring further to the drawings for a detailed description of the invention, there is shown a pressing machine frame 10 supporting a lower pressing buck 11. A press lever 12 is pivoted at 13 on the frame and the forward end thereof is attached to a press head 14 which rises and falls in rela-

tion to the buck. The rear end of the press lever 12 is provided with a counter-balancing weight 15 which may be just a little heavier in some instances than the head 14 thereby causing the machine to stand normally open. Furthermore the weight 15, or a tension spring or other appropriate means, causes the head 14 to lift off the work when the operator manually kicks down on a kick-off pedal means to be described.

A lever 17-18 is pivoted at 19 in the frame with the upper part 17 extending upwardly to connect with a toggle link 20. This lever is preferably L-shaped to simplify the construction, and the link 20 is pivotally suspended from the rear end of the press lever 12 while its lower end is pivotally connected to the upper end of the lever link 17 and thus it is observed how the parts 17 and 20 constitute a toggle which breaks rearwardly from the frame to lift the head 14 high from the buck and which moves forwardly toward straight position closing the head down upon the buck. The lower part 18 of the lever extends forwardly and substantially horizontally towards the front of the pressing machine and connects with the power means employed to impose high compression between the pressing jaw surfaces.

A handle bar 21 is carried by the pressing head or lever and overhangs the front margin of the head and is thus conveniently located to the operator who grasps with one hand the handle and draws down the head to bring the pressing members 14 and 11 into light contact, and the other hand of the operator is simultaneously employed to operate the motor means as will be explained, so that both hands are engaged away from the press jaws. It is to be appreciated that the operator necessarily must employ his hands to close the head upon the work and apply heavy pressure to the head and therefore this construction compels the operator to remove his hands from the region of the pressing jaws for the purpose of closing the press and thus the factor of safety is increased to the point where it is practically impossible for the operator to accidentally injure his hands by leaving them in the press too long when the machine is placed in operation.

Any suitable motor means in the form of an electric motor 25 is installed in the upper

portion of the pressing machine and drives a shaft 27 provided with a fly-wheel 26 and said drive shaft rotates a worm pinion 28 engaging with a worm wheel 29 driving a power shaft 30 at reduced speed with increased power output.

A control handle 31 oscillates a shaft 32 which swings a weighted trip 33 in and out to engage a clutch lever 34. The clutch lever 10 has connection with a clutching mechanism contained within the gear housing 35 whereby the operation of the power shaft 30 is placed under the control of the operator. The operator depresses the handle 31 which 15 swings the weighted trip 33 outwardly thus engaging the clutch lever 34 through the agency of a trip 24 pivoted on the weighted member 33 which acts to move the clutch lever 34 and throw the shaft 30 into driving 20 connection with the worm wheel 29 to cause the said power shaft, together with a cam or eccentric 36 fixed thereon, to be picked up by the motor shaft 27 and rotated through a movement of 180 degrees. Thus the cam 36 25 is driven to its lowermost position by actuating the control handle 31 and remains there until the operator again depresses the handle whereupon the cam 36 is driven upwardly 180 degrees to its original position. The 30 handle 31 returns to a normally upward position each time it is depressed and released by the operator's hand because the weighted pendulum member 33 and its trip 24 moves back past the top end of the clutch lever 34. 35 The motor 25 with the fly wheel 26 run continuously and the fly wheel possesses sufficient momentum to assist the power member or cam 36 to drive downwardly with a powerful revolving stroke under the most 40 trying conditions of heavy pressing.

A power thrust toggle consists of links 40 and 41 having their adjacent ends connected by a pin 42. In the present design, the pin 42 is anchored in the upper end of the link 45 41 and moves freely in a short slot 43 made in the lower end of the link 40. Thus I provide a freely floating lost motion connection 42-43 between the links constituting the toggle 40-41. The upper end of this toggle 50 is pivotally swung or suspended on the cam 36 while the lower end of the toggle is pivoted at 44 to the lever 18. Some suitable form of manually operated kick-off means is employed for breaking the toggle 40-41 55 forwardly to cause the press to open, and in this instance I show a pedal 45 integrally made with the link 41. This kick-off pedal extends forwardly to a position convenient to the operator and by thrusting downwardly 60 on the pedal the operator causes the press to quickly open.

Automatic means are employed to straighten the power thrust toggle 40-41 and in the present machine this device takes the form of 65 a weighted arm 47 extending outwardly from

the upper end of the link 40. It is to be understood that the upper end of the link 40 is constructed in the form of an eccentric strap to encompass the eccentric driver 36 and I preferably construct the arm 47 integrally with this eccentric strap. The function of the arm and weight 48 is to urge the links 40 and 41 rearwardly and thus the action of the weight pressing downwardly to swing the toggle link 40 clock-wise very 70 readily accomplishes this purpose because the lost motion connection 42-43 permits a slight freedom of motion in the linkage thereof sufficiently to cause the thrust toggle center pin 42 to move clock-wise until the 75 center line position thereof is passed. At one stage of the straightening movement of this thrust toggle, the center pin 42 moves into exact alignment with the plane of the power shaft 30 and pivot pin 44, and it is desirable that this center line position be slightly 80 passed in order that the toggle reach an over-straightened position to set the parts in locked relation. A reach lug 50 is made integrally with one of the toggle links, as for 85 example, the link 40. This lug reaches past the center pin 42 and engages the face of the lower link 41. A screw 51 carried by the reach lug 50 is adjusted so that the center pin 42 stops at a fixed point on an over-straightened position and thus the thrust toggle 40 and 41 is so set up and constituted that a heavy thrust may be transmitted therethrough without danger of the toggle 90 breaking open during the high pressure 100 thrust exerted by the cam and motor.

In the operation of the machine, assuming that the head is up the operator draws the head down manually to contacting position under light pressure which causes the toggle 105 20-17 to approach straight position but this toggle is usually adjusted so that it does not quite reach a straight line position, for, by causing the links 20 and 17 to remain normally in angular relation to each other, it 110 follows that this toggle collapses rearwardly more quickly by the downward pull of the weight 15 when the press begins to open. The jaw or head closing action causes the toggle 40-41 to move into a straight line 115 position, and the weight 48 places this toggle in an over-straightened locked position whereupon the operator presses downwardly on the handle 31 causing the cam 36 to drive downwardly on the thrust toggle to produce 120 high compression between the head and buck. The machine is now opened by again operating the clutching mechanism by pressing down on the handle 31 which causes the cam 36 to rotate to its uppermost position 125 as shown in Figure 3 whereupon the operator depresses the pedal 45 which breaks or collapses the toggle 40-41 forwardly thus causing the weight 15 to quickly open the machine.

The motor means cams the pressure on and off which causes the machine to operate smoothly and open quietly. The press is safe to operate because the operator must 5 close the press with one hand and throw in the clutching mechanism with the other. The power parts are all installed in the upper part of the press which is an advantage because the lower framework does not have 10 to be so heavily constructed and the motor parts are less likely to pick up dirt from the floor on which the press rests.

What I claim is:

1. A power pressing machine comprising 15 in combination, a frame, cooperating pressing jaws carried thereon, means to bring the jaw into contact, a toggle linkage connected with one pressing jaw and pivoted on the frame, a lever arm integral with the toggle linkage and projecting forwardly from that toggle link which is pivoted on the frame, another toggle linkage carried on the forward end of the lever arm and extending substantially vertical therefrom and adapted 20 to straighten and move into braced position when the jaws are brought into contact, and motor operated means connected with the upper end of the last named toggle linkage to exert a thrust thereon to move the lever 25 arm to compress the said contacting jaws.

2. A power pressing machine comprising 30 in combination, a frame, cooperating pressing jaws carried thereon, means to bring the jaws into contact, a toggle linkage connected with one pressing jaw and pivoted on the frame, a lever arm integral with the toggle linkage and projecting forwardly from that toggle link which is pivoted on the frame, another toggle linkage carried on the forward end of the lever arm and extending substantially vertical therefrom and adapted 35 to straighten and move into braced position when the jaws are brought into contact, motor operated means connected with the upper end of the last named toggle linkage to exert a thrust thereon and move the lever arm to compress the said contacting jaws, a control handle by which the motor means is started and stopped, and a kick-off means 40 cooperating with the last named toggle linkage for opening the press.

3. A power pressing machine comprising 45 in combination, a frame, cooperating pressing jaws carried thereon, means for closing the press to bring the jaws into contact, a toggle linkage connected with one pressing jaw and pivoted on the frame, a lever arm integral with the toggle linkage and projecting forwardly from that toggle link which is pivoted on the frame, another toggle linkage carried on the forward end of the lever arm and extending substantially 50 vertical therefrom and adapted to straighten and move into braced position when the jaws are brought into contact, a lost motion 55 connection being provided in the links of the second named toggle linkage to permit an easy straightening action, means for moving the said second named toggle linkage into a past center aligned position to lock the said toggle linkage past the center line, and power means cooperating with the second named toggle linkage to exert a thrust there- 60 through.

4. A power pressing machine comprising 65 in combination, a frame, cooperating pressing jaws carried thereon, means for closing the press to bring the jaws into contact, a toggle linkage connected with one pressing jaw and pivoted on the frame, a lever arm integral with the toggle linkage and projecting forwardly from that toggle link which is pivoted on the frame, another toggle linkage carried on the forward end of the lever arm and extending substantially vertical therefrom and adapted to straighten and move into braced position when the jaws are brought into contact, a lost motion connection being provided in the links of the second named toggle linkage to permit an 70 easy straightening action, means for moving the said second named toggle linkage into a past center aligned position to lock the said toggle linkage past the center line, and power means cooperating with the second named toggle linkage to exert a thrust there- 75 through.

5. A power pressing machine comprising 80 in combination, a frame, cooperating pressing jaws carried thereon, means for closing the press to bring the jaws into contact, a toggle linkage connected with one pressing jaw and pivoted on the frame, a lever arm integral with the toggle linkage and projecting forwardly from that toggle link which is pivoted on the frame, another toggle linkage carried on the forward end of the lever arm and extending substantially vertical therefrom and adapted to straighten and move into braced position when the jaws are brought into contact, a lost motion connection being provided in the links of the second named toggle linkage to permit an 85 easy straightening action, means for moving the said second named toggle linkage into a past center aligned position to lock the said toggle linkage past the center line, and power means cooperating with the second named toggle linkage to exert a thrust there- 90 through, control means to stop and start the power means, operator actuated means for breaking the second named toggle linkage, and means for opening the press independently of the operator after the said second toggle linkage has been broken.

6. A press comprising in combination, a frame, cooperating pressing members carried thereon, means for bringing the pressing members into contact, means for withdrawing the pressing members from contact, a closing toggle connected to one of the pressing members, a lever made integral with one of the links of the closing toggle, a power toggle having one end thereof pivotally connected with the lever, a power driven member connected with the other end of the power toggle to compress the contacting pressing members, a weight carried by the power toggle to straighten the links thereof of past center line position, and a kick-off pedal carried on the power toggle to break the power toggle to permit the press to open.

7. A press comprising in combination, a frame, cooperating pressing members carried thereon, means for bringing the pressing members into contact, means for withdrawing the pressing members from contact, a closing toggle connected to one of the pressing members, a lever arranged in the lower part of the frame and made integral with one link of the closing toggle and pivoted on the frame at the joinder point of the link and lever, motor means located in the upper 130

- part of the frame above above the lever, a power toggle connected with the lever and motor means and adapted to compress the contacting pressing members, automatic 5 means for straightening the power toggle past center line position when the press is closed, and means for breaking the power toggle to cause the press to open.
7. A machine comprising in combination, 10 a frame, cooperating pressing members carried thereby, means for bringing the pressing members into contact, a toggle for holding the members closed in contacting position, an L-shaped lever pivoted in the frame 15 and one end thereof forming one link of the aforesaid toggle, a motor, a connection established between the other end of the L-shaped lever and motor, and a kick-off pedal carried by the connection by which the press 20 is caused to open.
8. A machine comprising in combination, a frame, cooperating pressing members carried thereby, means for bringing the pressing members into contact, a toggle for holding the members closed in contacting position, an L-shaped lever pivoted in the frame and one end thereof forming one link of the aforesaid toggle, a power toggle connected with the L-shaped lever, an eccentric 25 strap made on one end of the power toggle, an eccentric driver confined in the strap, and motor means to operate the eccentric driver.
9. A machine comprising in combination, a frame, cooperating pressing members carried thereby, operating means for bringing the pressing members into contact, a power toggle acting on the means for holding the members closed in contacting position, motor 30 means cooperating with the power toggle to exert a thrust therethrough to compress the contacting pressing members, a weighted actuating member to move the power toggle toward straightened position, and means to move the toggle in the reverse position to 35 open the press.
10. A machine comprising in combination, a frame, cooperating pressing members carried thereby, means for bringing the pressing members into contact, a power toggle 40 connected with the means for holding the members closed in contacting position, an eccentric strap made on one end of the power toggle, an eccentric driver confined in the strap, a motor to operate the eccentric driver, 45 means for controlling the motor to start the eccentric driver, and a kick-off pedal integrally formed with one link of the aforesaid power toggle and adapted to break the toggle to open the press.
11. A machine comprising in combination, 50 a frame, cooperating pressing members carried thereby, a power toggle for holding the 55 members closed in contacting position, said power toggle being provided with a take-up lost motion connection in its links to cause 60 the said toggle to readily move into a past dead center position, an L-shaped lever pivoted in the frame and having one end connected with the power toggle, a connection established between the other end of the 65 L-shaped lever and a pressing member, and a motor cooperating with the power toggle to exert a thrust on the L-shaped lever to compress the contacting pressing members.
12. A pressing machine comprising in 70 combination, a frame, cooperating pressing members, a press lever pivoted in the frame and carrying a pressing member on one end thereof, a rightangular lever pivoted in the frame and having an upper toggle link and a lower horizontal lever, a link connecting the press lever with the upper toggle link of the lever thereby forming a press closing toggle, a power toggle having one end there- 75 of connected to the outer end of the horizontal lever part, and a power driven cam upon which the other end of the power toggle is pivotally suspended.
13. A pressing machine comprising in 80 combination, a frame, cooperating pressing members, a press lever pivoted in the frame and carrying a pressing member on one end thereof, a rightangular lever pivoted in the frame having an upper link part and a lower 85 horizontal lever part, a link connecting the press lever with the upper link part of the lever forming a press closing toggle, a power toggle having one end thereof connected to the outer end of the horizontal lever part, a power driven cam upon which the other end 90 of the power toggle is pivotally suspended, means cooperating with the cam suspended power toggle for urging said toggle toward straight line position, and kick-off means for 95 breaking the power toggle to open the press.
14. A pressing machine comprising in 100 combination, a frame, cooperating pressing members, a press lever pivoted in the frame and carrying a pressing member on one end thereof, a rightangular lever pivoted in the frame and having an upper link and a lower horizontal lever, a link connecting the press lever with the upper link of the lever forming a press closing toggle, a power driven 105 member, a thrust toggle suspended from the power driven member and connected to the lever, a lost motion connection joining together links constituting the thrust toggle, a weight carried by the thrust toggle to urge 110 its toggle links toward straightened position, and means for breaking the thrust toggle to 115 open the press.
- In testimony whereof I affix my signature.
ALBERT B. CLISSON.
